UNITED STATES PATENT OFFICE.

DAVY VANCE SICKMAN, OF DENVER, COLORADO.

HYDRAULIC CARTRIDGE.

1,278,393.

Specification of Letters Patent. Patented Sept. 10, 1918.

Application filed August 3, 1915. Serial No. 43,380.

To all whom it may concern:

Be it known that I, DAVY VANCE SICKMAN, a citizen of the United States, residing at the city and county of Denver and State of Colorado, have invented certain new and useful Improvements in Hydraulic Cartridges, and do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in hydraulic cartridges, my object being to provide a construction of this class equipped for automatically cutting off the liquid or other fluid from the cartridge when a piston member has been projected to the desired degree. This construction includes suitable valve mechanism connected with the piston member, the valve being closed when the piston member reaches its outward limit of movement. Provision is further made, in case the valve should fail to completely cut off the actuating fluid, whereby the piston may move somewhat farther, this auxiliary movement resulting in uncovering an escape port for the actuating fluid, thus relieving the piston member from the pressure incident to its working movement and preventing injury to the cartridge.

30 It is evident that this improvement may be employed in connection with cartridges having a single piston member in each chamber, or where the pistons are telescoping and of the reaction type as set forth in my previous application Serial No. 38,856, filed July 9, 1915.

Having briefly outlined my present improvement, I will proceed to describe the same in detail, reference being made to the accompanying drawing, in which is illustrated an embodiment thereof. In this drawing—

Figure 1 is an underneath view of a hydraulic cartridge equipped with my improvement, or a view looking in the direction of arrow 1, Fig. 4.

Fig. 2 is a detail elevation partly broken away and showing one of the piston members of the telescoping construction of piston employed in the cartridge shown in Fig. 1.

Fig. 3 is a sectional detail view of the wall located between the two piston members in

the telescoping style of piston disclosed in Fig. 1. In this view a valve coöperating with the piston members is shown in elevation.

Fig. 4 is a vertical section taken on the line 4—7, Fig. 1, viewed in the direction of the arrow 4, the parts being shown on a larger scale. In this view the two members of the telescoping piston have just commenced their outward travel.

Fig. 5 is a cross section of the cartridge taken on the line 5—5, Fig. 1 looking toward the right, the parts being shown on a larger scale.

Fig. 6 is a detail view partly in section illustrating the piston member coöperating with that shown in Fig. 2, these two views illustrating a piston composed of the two telescoping members.

Fig. 7 is a section taken on the line 4—7, Fig. 1, showing the piston members after having reached the points in their travel where a valve member for cutting off the passage of fluid to the pressure surface of one of said members is in the closed position.

Fig. 8 is a section showing a modified form of construction. This is a section taken longitudinally of a cartridge, the section line being indicated at 8—8, Fig. 9 looking toward the right.

Fig. 9 is a cross section of a cartridge taken on the line 9—9, Fig. 8.

Fig. 10 is a horizontal section taken on the line 10—10, Fig. 9.

Fig. 11 is an end view of the valve member of the form of piston shown in Figs. 8 and 9, being a view looking in the direction of arrow 11, Fig. 8.

Fig. 12 is a section similar to Fig. 7, but illustrating a modified form of construction. The section line in this view is designated 12—12, in Fig. 13 the view being toward the right.

Fig. 13 is a section taken on the line 13—13, Fig. 12, looking toward the right.

Fig. 14 is a view similar to Fig. 12, but showing a slightly modified form of construction, the piston also being projected to close the valve for cutting off the supply of motive fluid.

Fig. 15 is a cross section taken on the line 15—15, Fig. 14, the piston, however, being only slightly projected.

Fig. 16 is a section taken on the line 16, 110 Fig. 14, looking upwardly or in the direction of the arrow.

The same reference characters indicate the same parts in all the views.

Referring first to Figs. 1 to 7 inclusive let the numeral 5 designate the bar of a 5 cartridge which is provided with chambers adapted to receive telescoping pistons composed of two members 6 and 7. The piston member 6 is composed of a head 4, an upwardly projecting cylindrical wall 8, a hollow centrally located valve part 9, and two columns 10 which are secured to the head, the latter being approximately rectangular in shape as indicated in Fig. 1. The piston member 7 is composed of an upwardly projecting head 12 and a depending cylindrical wall 13, the lower portion of this wall being equipped with a collar 14 below which is located a gasket 15 held in place by a nut 16. Between the upper surface of the collar 14 and the head 12, this member 7 is provided on opposite sides with guide tongues 17 which engage counterpart grooves 18 formed in a ring 19 threaded into the upper extremity of a stationary cylindrical wall 20 15 which spaces walls 13 and 8 of the two piston members. The ring 19 engages the upper surface of the collar 14, when the piston member 7 is at its upward and outward limit of movement. It will thus be 20 understood that during the projection of the two piston members, they move in opposite directions, the member 7 upwardly and the member 6 downwardly. The wall 13 of the member 7 being annularly arranged within 25 and surrounded by an interposed wall 20, while the wall 8 of the piston 6 surrounds the interposed wall 20 and moves in contact therewith. The lower extremity of the interposed wall 20 is provided with a gasket 20 or cup leather 21 which is held in place by a nut 22, a metal washer 23 being employed between the nut and the gasket. This gasket 21 engages the inner surface of the wall 8 of the piston member 6 and forms a water 30 tight joint between the wall 8 and the wall 20. Threaded into a threaded opening 24 formed on the inner surface of an exteriorly projecting collar 25 at the lower extremity of the interposed wall 20, is an annularly 35 arranged sleeve or barrel 26 which is surrounded by an annular space 27 in which the wall 13 of the piston member moves during the projection of said member. The chamber 28 within the sleeve 26, is in communication with the chamber 27 by a port 29. The sleeve 26 is further provided with a port 30 located below the ring 22. The sleeve 26 is closed at the top as shown at 31 and open at the bottom as shown at 32. The part 40 31 of the sleeve is provided at the top with a port 33 in communication with a passage 34 which extends outwardly and downwardly through the wall of the sleeve, its lower extremity communicating by a port 35 with the annular space 28.

Within this space 28 is located an auxiliary valve 46 having a head 36 below which is located a cup leather 37 held in place by a nut 38. This valve is provided with a relatively long stem 39 extending downwardly from the head 36, its lower extremity being equipped with an exteriorly projecting collar 40. 70

When the parts of the cartridge are assembled, the valve 9 of the piston 6 is located within the annular space 28 of the sleeve 26. The upper extremity of this valve 9 is provided with a cup leather or gasket 41 which is held in place by screw 42 which is threaded into the valve 9 which 80 is hollow and interiorly threaded at the top for the purpose. The gasket 41 closely engages the inner surface of the sleeve 26 and forms a liquid tight joint. The auxiliary valve 46 is located within the annular space 85 28 of the sleeve 26 and its stem 39 is surrounded by the valve 9 of the piston 6. The screw 42 closely engages the outer surface of the stem 39, while the collar 40 of the valve stem fits closely within the space 90 surrounded by the valve 9 of the piston member 6. The upper extremity of the valve stem 39 is provided with a transverse perforation 43 which is in communication with a central longitudinal passage 44 extending 95 downwardly through the stem of the valve and open at the lower extremity thereof.

Each column 10 of the piston member 6 is hollow and provided at its upper extremity with a gasket 45 which is held in place by a 100 screw 47 threaded into the interiorly threaded upper extremity of the column. The upper end of each column is provided with an exteriorly projecting collar 48 which closely fits a chamber 49 formed in the cartridge 105 bar. When the piston member is in the closed position, there is an annular space 50 between the lower surface of the collar 48 and the upper extremity of a short sleeve or nut 51 which enters the lower extremity of 110 the chamber 50, being threaded into the bar from below, the latter being interiorly threaded for the purpose. The upper surface of this sleeve is arranged in opposing relation to the lower surface of the collar 48. A relatively heavy spirally arranged spring 52 surrounds the column 10 above the stop sleeve 51. The lower extremity of each column 10 is threaded into an opening 53 formed in the head 4, of this piston member. 115

Arranged within each chamber 49, is a valve 54 having a head 55 at its upper extremity which fills the chamber 49 and is provided with a gasket 56 held in place by nuts 57. This valve has a reduced stem 58 125 which is surrounded and closely engaged by a slip nut 47 of the column. The lower extremity of this valve stem is equipped with an exteriorly projecting collar 59 which fits closely within the column. Between the 130

screw 47 and the upper surface of the collar 59, there is an annular space 60 when the piston member 6 is at its upward limit of movement. This space 60 grows considerably shorter during the projection of the piston member and just before the piston member reaches its limit of outward movement, the lower extremity of the nut 47 engages the upper surface of the collar 59, and as the piston member reaches its normal limit of outward travel, the nut 47 of the column engages the shoulder 59 of the valve, and the collar 48 of the column engages the spring 52. The motive fluid for actuating the piston members enters the upper extremities of the chambers 49 by way of passages 62 which communicates with a longitudinal passage 63 (see Fig. 5). It must be understood that the motive fluid for piston projecting purposes, enters the two chambers 49 above the columns 10, there being two passages 62 for each piston, these passages communicating respectively with the upper extremities of the chambers 49 in which the columns 10 are located.

Each valve stem 58 is centrally provided with a longitudinal passage 64 which is open at its lower extremity and communicates at its upper extremity with a transverse perforation 65 which extends through the upper extremity of the stem 58, whereby both extremities of this perforation are in communication with the upper extremity of the chamber 49 above the top of the column 10.

From the foregoing description the operation of the invention as thus far described and so far as the construction disclosed in Figs. 1 to 7 is concerned, is as follows. The motive fluid as water, is supplied to the cartridge through a conduit 66 having a passage 67 which communicates with a port 68 in the forward extremity of the bar. This port communicates with a transverse passage 69 which registers with the passage 63 formed in a tube 71 set into the side of the bar. The water flows through the passages 62 into the upper extremities of the chambers 49 and thence through the perforations 65 into the passages 64 of the valve stems 58 and thence downwardly into the lower extremities of the chambers 60, thence through a transverse passage 72 formed in the head 4 of the piston 6, thence through a port 73 formed in the lower extremity of the valve 9, into the lower extremity of the space or chamber 74 within the valve 9, thence upwardly through the passage 44 in the stem 39, to the perforation 43 and thence into the upper extremity of the chamber 28 and thence through a port 75 into the passage 34 which extends both upwardly and downwardly from this port. The upper portion of the passage 34 leads to the upper extremity of the chamber 76 surrounded by the wall 13 of the piston member 7. The

water entering the upper extremity of this chamber, acts on the inner surface of the head of the piston member 7 and serves to project the latter, moving it in an upward direction.

From the port 75, the water travels downwardly in the passage 34 and thence through a port 35 into the chamber 28, around the valve 9 of the piston 6, the water in this case entering a shallow annular passage 77 surrounding the valve 9, and thence through the port 29 in the sleeve 26 into the lower extremity of the annular space 27, where it acts on the lower extremity of the piston member 7 for projecting purposes. Furthermore the water which enters the shallow annular space 77, also passes through the port 30 into the lower extremity of a chamber 79 inclosed by the cylindrical wall 8 of the piston member 6. The water when 85 in this position, acts upon the inner surface of the head of the piston member 6 and serves to project the latter. When this piston member 6 reaches the position shown in Fig. 7, whereby the lower extremity of

the screw 42 engages the upper surface of the collar 40 of the valve stem 39, the gasket 41 closes the inner extremity of the port 30 and cuts off the flow of motive fluid to the chamber 79 and consequently prevents 95 this fluid from passing to the pressure surface of the piston member 6, causing this member to cease its outward movement. At the same time the collar 14 of the piston member 7 will have reached the stop ring 100 19 of the interposed wall 20 which prevents further outward movement of this member.

If, however, by any possibility the motive fluid should leak past the gasket 41 and reach the pressure surface of the piston member 6 to further actuate this member, the columns 10 will be actuated sufficiently by virtue of the yielding capacity of the springs 52 to uncover relief ports 80 formed in the cartridge bar and communicating 110 with the chambers 49, thus allowing the motive fluid to escape and relieving the pressure surfaces of the piston 6. During the normal working of the cartridge and its pistons or when the piston member 6 ceases 115 its movement due to the closing of the port 30 by the gasket 41, the relief ports 80 remain closed by the gaskets 45.

During the further movement of the piston member 6 after the port 30 has been 120 covered by the gasket 41, and in the event that the motive fluid should leak past said gasket and reach the pressure surface of the piston 6 as heretofore explained, the valve members 46 and 54, will be actuated to the 125 extent of the further movement of the piston member, or until the relief ports 80 have been uncovered. The port 62 will be covered by gasket 56 and port 75 by gasket 37. The cartridge bar is provided with vent 130

ports 81 above the heads 55 of the valve members 54.

In the form of construction shown in Figs. 8 to 11 inclusive, the piston chambers 82 of the cartridge bar 83, contain but a single piston member 84. As shown in the drawing these piston chambers are open on the lower side of the bar and the pistons are intended to be projected downwardly. Each 10 piston is provided at its upper extremity with a cup leather or gasket 85 which is held in place by a screw collar 86 which is threaded into the body of the piston as shown at 87 and holds the gasket securely 15 in place. This gasket closely engages the inner surface of the wall of the piston chamber and forms a fluid tight joint. The cartridge bar is provided with a depending sleeve or barrel 88 whose upper extremity 20 is threaded as shown at 89 to enter a threaded opening formed in the top of the bar. Before the piston is inserted in the bar, the sleeve 88 is inserted in a cavity or central bore formed from the upper extremity 25 of the piston downwardly. The lower extremity of this sleeve is provided with a gasket 90 which is held in place by a disk 91 having an upwardly projecting interiorly threaded sleeve 92 which is screwed upon 30 the lower extremity of the sleeve 88. This disk 91 is provided with a central opening to receive the stem 93 of a valve 94 which when the piston is in the closed position engages the upper extremity of the sleeve 88 35 which is closed except for a perforation 95 which communicates with a passage 96 for motive fluid. The upper extremity or head 97 of the valve 94 fills the chamber of the sleeve 88, its outer edge being provided with 40 recesses 98 through which the motive fluid passes to the chamber 99 of the sleeve 88 when the piston is at its inward limit of movement. The disk 91 is further provided with interior recesses 100 through which the 45 motive fluid is allowed to pass from the chamber 99 to the pressure surface 101 of the piston. The piston is further provided with vertical grooves 102 through which the motive fluid travels upwardly to the pressure surface 103 of the upper portion of the piston. The central lower portion of the piston is bored to receive the head 104 of a screw which is applied to the lower extremity of the stem 93 of the valve 94. 50 Above the head 104 of this screw is a cavity 105 in which is located a heavy spiral spring 106. Below the head 104 of the screw the piston is counterbored to receive a nut 78 whose lower surface is flush with the bottom 55 of the piston wall, its upper surface engaging the head of the screw.

In the operation of this form of construction, as the motive fluid enters the passage 96 and flows through the port 95, it enters 60 the chamber 99 of the sleeve 88 and passes

thence to the pressure surfaces 101 and 103 of the piston as heretofore explained. As the piston moves out of its chamber in the bar in a downward direction, the valve member 94 travels with it and the movement of 70 the piston continues until the head 97 of the valve member engages the gasket 90, in which event the recesses 100 together with registering recesses formed in the gasket 90 will be closed, thus cutting off the motive 75 fluid from the pressure surfaces of the piston. If however the motive fluid should by any possibility leak past the head 97 of the valve member and reach the pressure surfaces of the piston and impart further movement thereto, such movement would be permitted by virtue of the yielding capacity of the spiral spring 106. This spring will permit sufficient movement to uncover a relief port 107 from which the motive fluid is normally cut off by the gasket 85. However when the abnormal movement of the piston just explained occurs, the gasket 85 passes below this port and allows the motive fluid to escape, thus relieving the piston from further travel. 80

In the form of construction shown in Figs. 12 and 13, the piston 108 is provided on opposite sides with columns 109 which are movable in auxiliary chambers 110. The 95 lower extremities of these columns are threaded into the base 112 of the piston as shown at 113. The lower extremity of a valve stem 114 of a valve 214 is threaded into a disk 115 to which a gasket 116 is applied being secured in place by a nut 117. This disk 115 is located in the bottom of a central chamber 217 formed in the body of the piston. The stem of the valve passes through a central opening in the bottom of a sleeve 118 which is substantially of the same construction as the corresponding element in Figs. 8 and 9. The upper extremity of the valve is equipped with a head or valve piece 119 having recesses 120 in its outer 105 edge to allow the motive fluid which enters the port 121 from the passage 122, to pass downwardly into the chamber 123 of the barrel or sleeve 118. This motive fluid passes through openings 124 in a gasket 125 and registering openings 127 in the bottom 110 of the sleeve. In this case the motive fluid acts on the lower extremity of the valve which being in the bottom of the chamber 217 of the piston, forms one of the pressure 115 surfaces of the piston. The motive fluid also passes through vertically disposed grooves 126, into a chamber 128 above the upper extremity of the piston and acts upon this extremity which constitutes a pressure surface. As the piston is projected to its normal limit of outward movement, the head 119 of the valve engages the gasket 125 and closes the perforations 124 in the gasket and prevents the motive fluid from reaching the 120 125 130

pressure surfaces of the piston. At the same time that the head or valve piece 119 reaches the gasket 125, collars 129 with which the upper extremities of the columns 109 are equipped, engage relatively heavy spiral springs 130 located in the bottoms of the chambers 110, these springs resting on nuts 131 threaded into the lower extremities of these chambers. In the event that the valve piece 119 should not be effective in preventing the passage of the motive fluid to the pressure surfaces of the piston, in other words if this motive fluid should leak past this valve piece and reach such pressure surfaces, the piston may be further projected without injury to the cartridge, by virtue of the yielding capacity of the springs 130. During the further projection of the piston due to the yielding of these springs, relief 20 ports 132 leading from the lower portion of the piston chamber 128 to the outer surface of the cartridge, are uncovered allowing the motive fluid to escape, thus preventing injury to the structure.

25 In the construction shown in Figs. 14 to 16 inclusive, a sleeve 133, receives the motive fluid in its chamber 134 from a passage 135 through a port 136. This motive fluid passes through a port 137 at the upper extremity of the sleeve and flows thence downwardly through a passage 138 and enters the chamber 134 through a port 139 located at the bottom of the sleeve. The upper extremity of the stem 140 of the valve 141, is 30 equipped with a gasket 142, which when the piston is at its normal limit of outward movement, closes the port 143 and prevents the motive fluid from entering the piston chamber 144 above the piston. At the same time the upper extremity of the valve stem through the medium of the gasket 142 closes ports 145 in the bottom of the sleeve 133 and cuts off communication between sleeve 133 and the piston chamber which the said sleeve 35 enters when the piston is in the closed position. If however the motive fluid by leaking past the gasket 142 should manage to reach the pressure surfaces of the piston, the upper extremities of the columns 147 which engage spiral springs 148, will yield to allow the piston to move sufficiently to uncover a relief port 149 through which the motive fluid escapes, relieving the pressure surfaces of the piston and preventing damage to the cartridge.

40 As the operation of the various forms of the apparatus has been described in connection with the description of each form, it is believed that further detailed explanation 45 of such operation will be unnecessary.

Attention is called to the fact that the sleeve or barrel 26 (see Fig. 4); 88 (see Figs. 8 and 9); 118 (see Figs. 12 and 13) and 133 (see Figs. 14 and 15), and columns 9 and 10, Figs. 4 and 7, while shown threaded

into the bar, must be understood as formed virtually integral therewith as by brazing or electric welding, in order to prevent any possible leakage which would result if their connection with the bar were by screw threads 70 only. These barrel members are indicated as threaded into the bar, for the purpose that it is necessary or at least highly desirable from a standpoint of convenience of construction, to form these devices separate 75 from the bar and afterward assemble them as the pistons are put in place.

Between the nut 78 and a shoulder on the piston 84, is located a gasket 150 which maintains a tight joint to prevent the escape 80 of the water when acting on the pressure surfaces 101.

Having thus described my invention, what I claim is,—

1. A hydraulic cartridge including a bar 85 having a chamber, a piston therein, means for introducing motive fluid to the chamber for the projection of the piston, and means for automatically cutting off the supply of motive fluid when the piston has reached its 90 desired limit of outward travel.

2. A hydraulic cartridge including a bar having a chamber, a piston therein, means for introducing motive fluid to the chamber for the projection of the piston, and means 95 actuated by the piston for automatically cutting off the supply of motive fluid when the piston has reached its desired limit of outward movement.

3. A hydraulic cartridge including a bar 100 having a chamber, a piston therein, means for introducing motive fluid to the chamber for the projection of the piston, and means carried by the piston for automatically cutting off the supply of motive fluid when the 105 piston has reached a predetermined limit of outward travel.

4. A hydraulic cartridge including a bar having a chamber, a piston therein, means for introducing motive fluid to the chamber 110 for the projection of the piston, and means carried by the piston for automatically cutting off the supply of motive fluid when the piston has reached a predetermined limit of outward travel, said last named means including a valve member.

5. A hydraulic cartridge including a bar having a chamber, a piston therein, means for introducing motive fluid to the chamber for the projection of the piston, and means 120 carried by the piston for automatically cutting off the supply of motive fluid when the piston has reached a predetermined limit of outward travel, said means including a valve member, the bar having a sleeve or barrel 125 into which the valve member extends and through which the motive fluid passes to the pressure surface of the piston.

6. A hydraulic cartridge comprising a bar having a main chamber and two auxiliary 130

chambers, a piston having a main member and two auxiliary members located respectively in the main and auxiliary chambers, the bar having a barrel member centrally arranged in the main chamber, the piston member having a valve extending into said barrel, and means for introducing motive fluid to the pressure surfaces of the main piston member through the said barrel, the said valve being arranged to cut off the motive fluid when the piston has reached a predetermined outward limit of movement, and springs in the auxiliary chambers adapted to be engaged by the auxiliary piston members for permitting further movement of the piston after the said valve is closed, the bar having a relief port communicating with the main chamber of the piston and arranged to be uncovered by the piston during such further movement.

7. A hydraulic cartridge including a bar having a main chamber and two auxiliary chambers arranged on opposite sides of the main chamber, a piston having a main member and two auxiliary members respectively located in the main and auxiliary chambers, the bar having a barrel member centrally arranged within the main chamber, the main piston member having a valve extending into the said barrel, means for introducing motive fluid to the pressure surfaces of the main piston member through the said barrel, the said valve being arranged to cut off the supply of motive fluid when the piston has reached a predetermined outward limit of movement, and springs located at the lower extremities of the auxiliary chambers and adapted to be engaged by the auxiliary piston members for permitting further movement of the piston after the said valve is closed, the upper extremities of the auxiliary piston members having exteriorly projecting shoulders adapted to engage the said springs.

8. A hydraulic cartridge including a bar having a main chamber and two auxiliary chambers, a piston having a main member and two auxiliary members respectively located in the main and auxiliary chambers, the bar having a barrel centrally located in the main chamber, the main piston member having a valve extending into said barrel, means for introducing motive fluid to the pressure surfaces of the main piston member through the said barrel, the valve being arranged to cut off the supply of motive fluid when the piston has reached a predetermined limit of outward travel, the lower extremities of the auxiliary chambers being closed, springs supported in the lower extremities of the auxiliary chambers, the upper extremities of the auxiliary piston members having collars adapted to engage said springs when the said valve is in the closed position, the springs serving to per-

mit further outward travel of the piston, the bar being provided with a relief port in communication with the auxiliary chambers and arranged to be uncovered by the auxiliary piston members during the further travel of the piston.

9. A hydraulic cartridge including a bar having a chamber, a piston therein, means for introducing motive fluid to the chamber for the projection of the piston, means actuated by the piston for automatically cutting off the supply of motive fluid when the piston has reached its desired limit of outward movement, said means including a valve.

10. A hydraulic cartridge including a bar having a chamber, a piston therein, means for introducing motive fluid to the chamber for the projection of the piston, means carried by the piston for automatically cutting off the supply of motive fluid when the piston has reached a predetermined limit of outward travel, said means including a valve.

11. A hydraulic cartridge including a bar having a chamber, a piston therein, means for introducing fluid to the chamber for the projection of the piston, means carried by the piston for automatically cutting off the supply of motive fluid when the piston has reached a predetermined outward movement, said last named means including a valve member, and a fluid controlling valve connected with said valve member.

12. A hydraulic cartridge including a bar having a chamber, a piston therein, means for introducing motive fluid for the projection of the piston, means carried by the piston for automatically cutting off the supply of motive fluid when the piston has reached a predetermined limit of outward travel, said means including a valve member, said bar having a sleeve or barrel into which the valve member extends and through which the motive fluid passes to the pressure surface of the piston, and a fluid controlling valve located within the barrel and connected and coöperating with the valve member to enable the latter to perform its function.

13. A hydraulic cartridge comprising a chamber, a barrel carried by the bar and centrally arranged within said chamber, a piston in the said chamber, means for introducing motive fluid through the barrel to the pressure surfaces of the piston, the latter being provided with a valve member extending into the barrel for cutting off the supply of motive fluid when the piston has reached the desired limit of travel.

14. A hydraulic cartridge comprising a bar having a chamber, a piston within the chamber, a barrel member carried by the bar and centrally arranged within the chamber, means for introducing motive fluid through the barrel to the pressure surfaces of the

piston, said piston having a valve member extending into the barrel member, one of said members having a gasket to facilitate the cutting off of the motive fluid when the 5 piston has reached the desired limit of outward travel.

15. A hydraulic cartridge comprising a bar having a chamber, a piston therein, means for introducing motive fluid to the pressure surfaces of the piston, the piston having a valve member to cut off the supply of motive fluid when the piston has reached

a predetermined limit of outward travel, and yielding means for permitting the further movement of the piston after the valve 15 member thereof is in the closed position, the bar having a relief port arranged to be uncovered by such further piston movement.

In testimony whereof I affix my signature in presence of two witnesses.

DAVY VANCE SICKMAN.
